UNITED STATES PATENT OFFICE.

JOHN E. MITCHELL AND DENNIS PARKS, OF ST. LOUIS, MISSOURI, ASSIGNEES TO ALSOP PROCESS COMPANY, OF ST. LOUIS, MISSOURI, A CORPORATION OF MISSOURI.

APPARATUS FOR SUBJECTING AIR TO ELECTRIC DISCHARGES.

No. 817,082.

Specification of Letters Patent.

Patented April 3, 1906.

Application filed January 3, 1906. Serial No. 294,392.

To all whom it may concern:

Be it known that we, JOHN ELVIN MITCHELL and DENNIS PARKS, citizens of the United States, residing at St. Louis, in the State of Missouri, have invented new and useful Improvements in Apparatus for Subjecting Air to Electric Discharges, of which the following is a specification.

This invention relates to certain new and useful apparatus for subjecting air to the action of an electric discharge; and the objects of the invention are to provide a self-contained apparatus presenting the minimum number of parts and one which is capable of very rapid operation, so that a large number of electric discharges per minute may be produced as compared with machines of the same general character heretofore used.

With the above stated general objects in view, as well as other objects which will appear from the specification and claims to follow, the invention resides in the novel construction, combination, and co-operation of parts hereinafter described, and particularly pointed out in the claims.

We have shown in the drawings as an embodiment of our invention an apparatus designed for producing what has come to be known as the "flaming" electric discharge; but it will be apparent to those skilled in the art that the invention hereinafter described and the principles of operation involved therein are applicable to the production of other characters of electric discharge.

In the drawings, Figure 1 is a sectional side elevation illustrating a complete apparatus embodying our invention, and Fig. 2 is a sectional end elevation of the same.

Referring now to the drawings, the apparatus will be seen to comprise as to its main portions an electrifying-chamber 1, pump-cylinders 2 3, and an induction-coil 4.

The frame of the machine, (indicated generally by 5,) supporting the induction-coil and forming the electrifying-chamber and the pump-cylinders, is cast from metal, and practically the entire main structure or frame may be made at a single casting. At opposite ends of the electrifying-chamber 1 there are provided in the respective end walls of the frame air-chambers 6 7, which communicate, through tapered openings 8 9 in the end

walls of said electrifying-chamber, with the latter.

10 indicates a normally stationary electrode which is horizontally disposed and slidably mounted centrally of the chamber 1 in porcelain or other non-conducting bearings 11, which are in turn mounted in supports 12. At opposite ends of the electrode 10 are mounted contact-blocks 13 14, removably secured thereon by means of screws or other fastening devices 15. In employing the word "electrode" hereinafter we intend to include the electrode proper, 10, and its contact-blocks 13 14, as it is obvious that we may dispense with contact-blocks and simply use the opposite ends of the electrode itself for contact purposes. For the sake of economy, however, it is desirable to have removable contact-blocks, as when they have worn away they may be removed and new contact-blocks inserted on the ends of the electrode, and thus obviate having to substitute entirely new electrodes, as would be the case if the contact-blocks were dispensed with.

16 17 indicate movable electrodes which are mounted in the upper ends of arms 18 each of which is fixedly secured on the outer end of a piston-rod 19 and 20, respectively. The inner ends of the piston-rods 19 and 20 are secured in opposite sides of a coupler 21, which is provided with a vertically-disposed slot 22, in which works a pin 23, mounted eccentrically on a wheel 24, fixed on a shaft 25, which shaft is driven through the medium of a pulley 26 from any source of power. As the shaft revolves the pin 23, working in the slot 22, will cause the pistons 19 and 20 to be reciprocated back and forth, and this reciprocation of the pistons will cause a corresponding movement of the electrodes 16 and 17, bringing them alternately into and out of contact with the respective contact-blocks 13 and 14.

27 indicates a generator of electricity, from one side of which a conductor 28 leads to the induction-coil 4. From the induction-coil 4 a conductor 29 leads to a metal shoe 30, which is mounted on the electrode 10, but so as to permit the electrode to slide freely through the same. In order to insure a constant electrical contact between the shoe 30

and electrode 10 and also to prevent the shoe 30 from turning, the under side of said shoe is shown extending down a considerable distance below the electrode 10, and this pendant portion 31 may be made of any desired weight to carry out the purposes above indicated. From the other side of the generator 27 a conductor 32 leads and is electrically connected with the electrodes 16 and 17. This connection is made with the electrodes themselves or with the metallic arms 9 supporting them. The pump-cylinders 2 and 3 are open at their inner ends, and mounted on each of the piston-rods 19 20 is a piston 33, working in the corresponding pump-cylinder and provided with a flap or other valve 34 for the admission of air.

35 indicates ports connecting the respective cylinders 2 and 3 with the air-chambers 6 and 7 and which are controlled by valves 36, permitting air to pass from the pump-cylinders 2 3 into said chambers, but which close to prevent air from being drawn out of said chambers.

37 indicates a removable top of the electrifying-chamber, said top being provided with an outlet 38, from which the modified air passing through the apparatus may be conducted into the presence of the flour to be treated.

The operation of the apparatus will be readily understood and is as follows: Assuming the apparatus to be in operation, as the piston-rod 19 moves inward the piston 33 will be moved toward the front end of its cylinder, closing by suction the valve 36 and opening the valve 34 to permit air to pass into the cylinder and in front of said piston. This movement of the piston-rod will also cause the electrode 16 to be brought into contact with the contact-block 13. In the outward movement of the piston-rod 19 the piston 33, moving to the back end of its cylinder, will close the valve 34 and force air through the port 35 into the air-chamber 6. This movement will also cause the electrode 16 to be removed from contact with the contact-block 13, and as these parts separate the current in the form of the flaming or other character of electric discharge will pass between them. At the same time the air which was forced into the chamber 6 will pass out of said chamber through the port 8, which surrounds the electrode 16, and be discharged into the immediate vicinity and on all sides of the electric discharge, and thus be thoroughly subjected to the modifying action of the said discharge. On the other side of the apparatus, which works in alternation with the side just described, the same operations as outlined above occur, and as the electrode 16 moves out of contact with the contact-block 13 the electrode 17 will be moving toward the contact-block 14. When the electrode 17 comes in contact with the contact-block 14, the cur-

rent will be short-circuited from the electrode 16 and the electric discharge occurring between said electrode and the contact-block 13 will be extinguished or dissipated. In practice, however, we provide for breaking or extinguishing the flame or electric discharge by means of the blast of air passing from the apertures 8 9 at each end of the electrifying-chamber before the electrodes at the opposite end have been moved into contact, thereby preventing a larger flow of current than is necessary. This operation also increases the efficiency of the flame in modifying the air.

The above-described machine is adapted to operate at a high rate of speed and to give the necessary contact between the electrodes, while at the same time avoiding injury by striking them together. The stationary electrode, as already described, is adapted to yield or slide back and forth in its bearing in the metal shoe 30, and for ordinary work said electrode is caused to slide or yield about one-fourth of an inch in each direction as the movable electrodes come into contact with it at each end of the stroke from opposite directions, which operation permits ample contact between the electrodes to enable the coil 4 to become saturated with electricity, so that as the electrodes are drawn apart the resultant induced current will supply the requisite potential for maintaining the electric discharge.

Our machine is extremely compact, simple, and durable, requiring a very little space and power; but at the same time it possesses great efficiency in electrifying the air by reason of the large number of arcs which may be drawn out per minute.

It will be seen that the eccentric-pin 23 through the connections described operates all the moving parts of the machine and that the pump-pistons and movable electrodes work in unison, so that the air is discharged through the respective ports 8 and 9 immediately the arc is formed or the electric discharge commences. Of course the action of the pumps is also utilized in forcing the air from the electrifying-chamber through the outlet 38, from whence, as stated, it is or may be conducted into the presence of the flour to be treated.

The complete apparatus is mounted on a wooden base 39.

We claim—

1. In an apparatus for modifying air by the electric discharge, in combination with a yieldably-mounted electrode, a pair of electrodes reciprocable into and out of contact with opposite ends thereof, said electrodes being connected with a suitable source of electricity.

2. In an apparatus for modifying air by the electric discharge, in combination with a slidably-mounted electrode, a pair of electrodes reciprocable into and out of contact

with opposite ends thereof, said electrodes being connected with a suitable source of electricity.

3. In an apparatus for modifying air by

5 the electric discharge, in combination with a yieldably-mounted electrode, a pair of synchronously-movable electrodes reciprocable into and out of contact alternately with opposite ends of said electrode, said electrodes 10 being connected with a suitable source of electricity.

4. In an apparatus for modifying air by the electric discharge, in combination with a slidably-mounted electrode, a pair of electrodes reciprocable into and out of contact with opposite ends thereof, and means for connecting up said electrodes with a source of electricity involving a shoe loosely mounted on said slidable electrode.

20 5. In an apparatus for modifying air by the electric discharge, in combination with an electrifying-chamber having an end wall provided with an aperture and having an outlet, an electrode mounted in said chamber, 25 a second electrode, and means for reciprocating it through said aperture into and out of contact with said first-named electrode, said electrodes being connected with a source of electricity, and means for forcing a blast 30 of air through said aperture.

6. In an apparatus for modifying air by the electric discharge, in combination with an electrifying-chamber having an end wall provided with an aperture and having an outlet, 35 a second electrode, and means for reciprocating it through said aperture into and out of contact with said first-named electrode; said electrodes being connected with a source 40 of electricity, and means for forcing a blast of air through said aperture simultaneously with the outward or separating movement of said last-named electrode.

7. In an apparatus for modifying air by 45 the electric discharge, in combination with an electrifying-chamber having oppositely-disposed apertures and provided with an outlet, an electrode mounted in said chamber in line with said apertures, a pair of electrodes 50 reciprocable through said apertures into and out of contact with opposite ends of said first-named electrode, said electrodes being

connected with a source of electricity, and means for forcing a blast of air through said apertures simultaneously with the outward 55 or separating movement of the respective reciprocable electrodes.

8. In an apparatus for modifying air by the electric discharge, in combination with an electrifying-chamber having oppositely-disposed apertures, a pair of pump-cylinders having valve-controlled communication with said apertures, plungers in said cylinders, an electrode in said electrifying-chamber, a pair of electrodes reciprocable through said apertures into and out of contact with opposite ends of said electrode, and means for simultaneously operating said pair of electrodes and said plungers.

9. In an apparatus for modifying air by 70 the electric discharge, in combination with an electrifying-chamber, an electrode yieldably mounted therein, a pair of air-pumps having pistons, a pair of electrodes operatively connected to said pistons, means for 75 reciprocating said pistons alternately in opposite directions whereby said pair of electrodes are also reciprocated in opposite directions into and out of contact with said yieldable electrode, and ducts provided in 80 said apparatus for conveying air from said pumps into the presence of the electric discharges produced at opposite ends of the latter electrode.

10. In an apparatus for modifying air by 85 the electric discharge, in combination with an electrifying-chamber, a pair of electrodes connected with a suitable source of electricity and one of which is reciprocable into and out of contact with the other within said 90 chamber; and an air-pump for forcing air into the presence of the electric discharges occurring between said electrodes, said reciprocable electrode being connected to and movable simultaneously and in unison with 95 a movable member of the air-pump.

In testimony whereof we have hereunto set our hands in presence of two subscribing witnesses.
